BED PAN LINER

Wayman R. Spence, 1479 Devonshire Drive,
Salt Lake City, Utah 84108

Filed Aug. 15, 1968, Ser. No. 13,153

Term of patent 14 years

Int. Cl. D24—02; D28—01

U.S. Cl. D83—1

FIG. 1

FIG. 2

FIG. 3

FIG. 6

FIG. 4

FIG. 5

FIG. 1 is a front and side perspective of a bed pan liner showing my new design;

FIG. 2 is a top plan view thereof;

FIG. 3 is a bottom view of the bed pan liner;

FIG. 4 is a front elevation view thereof;

FIG. 5 is a rear elevation view of my design for a bed pan liner; and

FIG. 6 is a side elevation view of the bed pan liner.

I claim:

The ornamental design for a bed pan liner, as shown.
